UNITED STATES PATENT OFFICE.

SAMUEL J. WENTWORTH, OF NEWPORT, KENTUCKY, ASSIGNOR, BY MESNE ASSIGNMENTS, TO UNITED SHOE MACHINERY CORPORATION, OF PATERSON, NEW JERSEY, A CORPORATION OF NEW JERSEY.

LIP-TURNING MACHINE.

1,282,340.

Specification of Letters Patent.

Patented Oct. 22, 1918.

Application filed December 18, 1915. Serial No. 67,541.

To all whom it may concern:

Be it known that I, SAMUEL J. WENTWORTH, a citizen of the United States, residing at Newport, in the county of Campbell 5 and State of Kentucky, have invented certain new and useful Improvements in Lip-Turning Machines; and I do hereby declare the following to be a full, clear, and exact 10 description of the invention, such as will enable others skilled in the art to which it app pertains to make and use the same.

This invention relates to lip-turning machines.

The primary object of the present invention is to improve the construction and mode 15 of operation of lip-turning machines to better adapt the sole produced for good shoe making.

The lip-turning machines now in commercial use for turning back the channel lip on 20 outsoles, employ a rotary tool which rides over the face of the channel and lip to turn the lip back against the sole preparatory to the stitching operation. In the turning the 25 lip back, the rotary tool glazes the face of the channel and groove and the under face of the lip. These glazed portions are objectionable because they do not allow the lip to be effectively cemented back into the channel after the stitching operation.

One feature of the invention contemplates the provision in a lip-turning machine of an improved lip-setting tool arranged to reciprocate across the lip in a plane substantially parallel with the plane of the sole to 35 turn the lip down against the surface of the sole. In turning the lip down upon the sole, the tool acts only on a small portion of the lip and leaves it in good condition to 40 be cemented back into the channel.

In addition to the features of invention above referred to, the present invention also consists in certain devices and combinations of parts hereinafter described and claimed, 45 the advantages of which will be obvious to those skilled in the art from the specific description of the preferred embodiment of the invention hereinafter contained.

The several features of the invention are 50 illustrated in the accompanying drawings, in which Figure 1 is a plan view of a lip-turning machine embodying the invention in its preferred form; Fig. 2 is a side ele-

vation of the lip turning machine; Fig. 3 is a rear end elevation partly in section, of 55 the lip-turning machine; Fig. 4 is a front end elevation of the lip-turning machine; Fig. 5 is a detail view in vertical section showing the upper feed roll and lip-turning tool; and Fig. 6 is a detail view in vertical 60 section showing the feed rolls.

The machine illustrated in the drawings is designed for turning back the lip on a McKay outsole. The sole is supported on a feed roll 10 and clamped against this feed 65 roll by means of a channel feed roll 12. The sole is guided in its movement by a plow 14 which has a face 16 adapted to ride in a groove of the sole and bear against the shoulder of the lip. As the sole moves past 70 the plow the lip is turned up to a substantially vertical position and is then turned back against the surface of the sole by a lip-turning tool 18.

The supporting feed roll 10 is built up in 75 sections (see Figs. 2 and 6). A feeding section 20 is located in the axis upon which the sole is turned and is fixed to a driving shaft 22 journaled in the main frame 24 of the machine. The circumferential edge of the 80 section 20 is provided with teeth 26, and the edge is comparatively narrow so that, when the sole is turned about a sharp angle, the teeth will not chew up the sole. The other section 28 of the feed roll is loosely mounted 85 upon the shaft 22 adjacent the section 20, but is connected for movement with the feeding section by a pin 30 fixed in the section 20 which projects through a slot 32 in the section 28 (see Fig. 4). The circumferential edge of the section 28 is also provided 90 with teeth and ordinarily assists section 20 in feeding the sole. With this construction, a series of two or more sections can be mounted adjacent one another to 95 give a substantial bearing face for supporting the sole and to give a sufficient biting area for the feed teeth in carrying the sole through the machine. The mounting of the sections of the feed roll for differential 100 movement facilitates feeding the sole around a sharp angle, and the teeth of the sections do not injure the face of the sole. When turning the sole about a sharp angle the feeding section 20 being located in the axis 105 on which the sole is turned, will act to feed

the sole, and the movement of the sole by the operative in bringing it around an angle will move the loose section 28 relatively to the feeding section.

- 5 The channel feed roll consists of a series of teeth 34 formed on a sleeve 36 which is fixed on the end of a hollow shaft 38 journaled in a bearing 40 on a swinging frame 42. The teeth 34 are arranged to engage
- 10 the channel of the sole at a portion opposite the feed roll 10, and the roughening of the face of the sole channel by the teeth 34 aids in forming a good cementing surface to which the lip may be cemented.
- 15 The plow 14 is mounted on a stationary plate 44 immediately in front of the channel feed roll, and its working face 16 is close to the bite of the feed rolls to adapt the machine for working on soles having
- 20 sharp toes. The plate 44 is held in position by means of a pair of braces 46 which are fastened to a split collar 48 mounted on the end of the bearing 40 of the swinging frame 42.
- 25 After the lip has been turned by the plow, it is engaged by the lip-turning tool 18 and turned over against the face of the sole. The lip-turning tool consists of a hammer fixed to the end of a plunger 50
- 30 slidably mounted within the hollow shaft 38. The working face of the hammer is arranged above the face 16 of the plow and is reciprocated back and forth across the lip in a plane substantially parallel with
- 35 the face of the sole to turn the lip down against the sole. The lip-turning tool or hammer 18 is guided in a rectangular slot 52 in the plate 44 which holds it in alignment. The plunger 50 extends beyond the
- 40 end of the shaft 38 and is provided with an arm 54 which is connected by means of a universal coupling 56 and connecting rod 58 with an eccentric 60 on the main driving shaft 62. The rear end of the plunger is
- 45 held in alignment (Figs. 2 and 3) by means of a plate 64 which is mounted between a collar 66 on the end of the plunger and a collar 68 on the end of a stud 70 mounted in the main frame of the machine.
- 50 To provide for treatment of different thicknesses of soles, the channel feed roll and lip-turning tool are mounted in a swinging frame and arranged to be moved relatively to the supporting feed roll to automatically adjust themselves for the different thicknesses of soles. The swinging frame 42, Fig. 1, is pivotally mounted upon an auxiliary shaft 72 which is journaled in the main frame of the machine. The shaft 38
- 55 and the plunger 50, which carry the channel feed roll and the lip-turning tool respectively, are mounted in the bearing 40 of the swinging frame. When the swinging frame is oscillated on the shaft 72, the lip-turning
- 60 tool and feed roll move with it. The uni-
- 65

versal coupling 56 on the plunger 50 permits this movement without interfering with the reciprocation of the lip-turning tool, and the plate 64 has a slotted connection 74 with the stud 70 to provide for the swinging movement of the frame. An arm 76 projecting from the bearing 40 of the swinging frame 42 is normally held against a set screw 78 in the machine frame by a spring 80 which is connected between the arm 76 and a bolt 82 mounted in the base of the machine frame. When turning the lip on the sole, the spring 80 presses the channel feed roll and plow against the sole and the set screw 78 prevents an excess pressure on the sole. The spring 80 will automatically adjust the channel feed roll relatively to the supporting feed roll for different thicknesses of soles, and the set screw may be adjusted to limit their relative position. The bolt 82 has a wing nut 84 by which the tension of the spring can be adjusted to vary the clamping effect of the feed roll upon the sole. To separate the feed rolls for the insertion and removal of work, the frame 42 may be rotated by a foot treadle (not shown) which is connected by means of a rod 86 with an arm 88 projecting from the side of the frame.

The feed rolls and lip-turning tool are operated through connections with the main driving shaft 62. The shaft 62 is provided with a step driving pulley 90 which may be connected with a source of power by the belt 92. The lip-turning tool is reciprocated at high speed by the eccentric 60 on the shaft 62, and to properly proportion the speed of the feed rolls the auxiliary shaft 72 for driving the feed rolls is geared to the main shaft by a worm 94. The feed rolls are driven at the proper relative speed and in opposite directions by a train of gearing which consists of a gear 96 pinned to the auxiliary shaft and meshing with a gear 98 loosely mounted upon the stud 70, a gear 100 pinned to the gear 98 (Fig. 3) and meshing with a gear 102 on the supporting feed roll shaft, and a gear 104 loosely mounted on the auxiliary shaft, the gear 104 also meshing with a gear 106 fixed to the channel feed roll shaft.

To assist the operative in guiding the shoe, the machine is provided with an edge guide which consists of a roll 108 for engaging the edge of the sole which is mounted on a slide 110. The slide 110 is supported on a rod 112 mounted in the split collar 48 and is pressed toward the feed rolls by a spring 114. The movement of the slide is limited by means of a pin 116 mounted in the rod 112 and projecting through a slot 118 in the slide.

While the invention has been illustrated for use in turning the lip on McKay soles, obviously it can be modified to be used for

turning over the lip on any type of a sole. The feed rolls are particularly adapted to clamp the sole in position and to properly support it while the lip is being turned down. By supporting the sole on the circumferential edge of the feed rolls, a molded sole can be operated upon as readily as a flat sole. The compact arrangement of the lip-turning tool, plow, and feed rolls, facilitates 10 the use of the machine in working on pointed toes. The supporting feed roll, further, particularly adapts the machine for working on soles with sharp toes. The character of tools used in turning over the lip leaves the 15 lip in an excellent condition to be cemented back into the channel.

Having thus specifically described a preferred form of the invention, what is claimed as new is:—

20 1. A lip-turning machine having, in combination, feed rolls arranged to engage opposite sides of a lipped sole with their circumferential faces, a lip-turning tool constructed and arranged to turn the lip down 25 against the sole, and means to reciprocate the tool across the lip.

2. A lip-turning machine having, in combination, a support for a lipped sole, a lip-turning tool arranged to reciprocate in a 30 plane above and substantially parallel with the plane of the supported sole and having its work engaging portions located wholly above the plane of the face of the sole, and means to reciprocate the tool to carry it back 35 and forth across the lip to turn the lip down against the face of the sole.

3. A lip-turning machine having, in combination, means for supporting and feeding a lipped sole, a plow for turning up the lip 40 of the sole having a face for engaging the sole, a lip-turning tool having its work engaging portions located wholly above the face of the plow for turning the lip back against the surface of the sole, and means to 45 reciprocate the tool back and forth across the lip in a plane substantially parallel with the plane of a supported sole.

4. A lip-turning machine having, in combination, means for supporting and feeding 50 a lipped sole, a lip-turning tool for turning back the lip against the surface of the sole, means for moving said tool with relation to the supporting means to adjust it for operating on different thicknesses of soles, and 55 means for reciprocating the tool.

5. A lip-turning machine having, in combination, a feed roll mounted on a fixed shaft

having an axis substantially parallel with the plane of movement of a sole, a feed roll mounted on a movable shaft having an axis 60 substantially parallel with the axis of the first mentioned shaft, a lip-turning tool mounted for movement with the movable shaft toward and from the fixed shaft, means for rotating said shafts, and means for actuating the tool to turn the lip over against the surface of the sole.

6. A lip-turning machine having, in combination, means for supporting and feeding a lipped sole, a lip-turning tool having its 70 work engaging portions located wholly above the plane of the face of the sole and arranged to turn the lip down against the face of the sole, and means to reciprocate the tool back and forth across the lip in its 75 turned down position in a plane substantially parallel to the plane of the sole.

7. A lip-turning machine having, in combination, a lip-turning tool, and means for feeding a channeled sole to the tool comprising, 80 a channel roll for engaging the sole channel with its circumferential face, and a supporting roll for engaging the sole with its circumferential face at a portion opposite the channel.

8. A lip-turning machine having, in combination, means for supporting and feeding a lipped sole comprising, a sole support and a roll engaging with its periphery the lipped surface of the sole outside of the lip, and 90 provided at its end with a recess, a lip-turning tool operating in said recess, and means for actuating said tool.

9. A lip-turning machine having, in combination, mechanism for feeding and supporting a lipped sole comprising, a sole support and a roll engaging with its periphery the lipped surface of the sole outside of the lip, a plunger mounted within the roll, a lip-turning tool attached to said plunger, and 100 means to actuate the plunger.

10. A lip-turning machine having, in combination, mechanism for supporting and feeding a channeled sole comprising, a channel engaging roll and a sole supporting roll 105 opposite the channel roll, said rolls being mounted on driving shafts, a movable frame in which the channel roll shaft is journaled, a lip-turning tool mounted in said frame, means to actuate the tool and rolls, and a 110 spring acting on the frame to clamp the sole between the rolls.

SAMUEL J. WENTWORTH.
